UNITED STATES PATENT OFFICE

2,605,081

COOLING MEANS FOR GAS TURBINE
WHEELS

Joseph S. Alford, Nahant, Mass., assignor to General Electric Company, a corporation of New York

Application April 25, 1946, Serial No. 664,852

3 Claims. (Cl. 253—39.15)

1

This invention relates to an improved arrangement for cooling the disk of a high temperature turbine bucket wheel, specifically to a novel form of combined cooling cap and exhaust hood for a single stage axial flow gas turbine wheel. The invention is particularly adaptable to gas turbines such as those used for driving a compressor to supercharge a reciprocating internal combustion engine.

An object of the invention is to provide an improved arrangement for cooling the downstream or exhaust side of the disk of a high temperature turbine bucket wheel.

Another object is to provide an improved form of combined exhaust hood and radiation type cooling cap for a gas turbine such as those used in turbosuperchargers.

A further object is to provide a cooling cap and exhaust hood arrangement which is simple in construction and can readily be disassembled for inspection and servicing.

A still further object is to provide an improved form of radiation type cooling cap for turbine disks.

Other objects and advantages will be apparent from the following description taken in connection with the accompanying drawings, in which Fig. 1 is a sectional view of a gas turbine having an exhaust hood and cooling cap in accordance with the invention; Fig. 2 is an end view, partly cut away, taken in the direction of the arrows 2—2 in Fig. 1; and Fig. 3 is an enlarged sectional view of a portion of the structure shown in Fig. 1.

Referring now to Fig. 1, a turbine bucket-wheel consisting of a disk 1 with a circumferential row of buckets 2 is secured, as for instance by welding, to a flanged shaft 3 supported in suitable bearings (not shown) in a bearing housing 4. Motive fluid is supplied to the flanged inlet opening 5 of an annular nozzle-box 6, which has a cast nozzle diaphragm 7 defining a ring of circumferentially spaced nozzles 8.

Surrounding the bucket-wheel is an annular flange 9, shown in the drawings as being formed integral with the nozzle-box 6. This flange serves to support the exhaust hood 10 and cooling cap 11.

Exhaust hood 10 consists of a casing formed of sheet metal and having at one side a circular opening arranged to surround the bucket wheel. As may be seen more clearly in Fig. 3, the means for supporting the cooling cap and exhaust hood consists of a flanged ring 12, which may be seam-welded to the axially extending flange 9.

2

A ring 13, Z-shaped in cross section, has a radially inner portion secured by a circumferential row of threaded fastenings 15 to the flange 12. The radially outer portion of Z-ring 13 forms a flange to which is secured exhaust hood 10 by means of a circumferential flange 16, which may be welded to the exhaust hood in the manner indicated in Fig. 3. The exhaust hood flange 16 may be secured to Z-ring 13 by any suitable clamping device, as for instance a quick-detachable "band clamp" 17. The clamping device comprises a split ring, U-shaped in cross section, and having the split ends of the ring drawn together by means of a bolt 18 arranged in suitable lugs 19 welded to the respective ends of the split ring. Such quick-detachable clamping bands are well-known in the art, and further details of the device shown in the drawings are not necessary to an understanding of the present invention.

The exhaust hood 10 is provided with a discharge portion 20, which may be connected to an exhaust gas conduit (not shown), or may be shaped to define a nozzle 21 arranged to discharge the turbine exhaust gases directly into the atmosphere. Nozzle 21 may be designed to produce a certain amount of jet thrust, when used in an aircraft.

The cooling cap 11 is of a type known as a "radiation" cooling cap because the coolant does not contact the turbine wheel directly, heat being transferred from the bucket-wheel to the adjacent outer walls of the cap by radiation and convection. This type of cooling cap has been previously disclosed in U. S. Patents 2,364,037 and 2,370,694, granted November 28, 1944 and March 6, 1945 respectively, on applications of Chester W. Smith. The cooling cap shown in Figs. 1 and 2 consists of an outer dome-shaped member 22 and an inner, concentric dome 23. The central portion of dome 23 may be secured to dome 22 as by spot-welding at the location 24 in Fig. 1. Arranged between the outer circumferential portions of the domes 22, 23 are a plurality of concentric rings 25, Z-shaped in cross section, and welded together and to the domes in a manner which will be obvious from Figs. 1 and 3. It will be seen that rings 25 form outer concentric annular ribs facing the hot turbine wheel disk and corresponding annular ribs extending in the opposite direction and projecting into the coolant inside the cooling cap, as will appear more clearly hereinafter. Thus, the rings 25 serve as cooling fins for receiving heat by radiation and convection from the hot turbine

wheel disk 1 and transferring it to the coolant supplied to the cooling cap.

At diametrically opposite locations, the outer cooling cap dome 22 is provided with radially extending slots 26a and 26b. Secured to the outer surface of dome 22, as for instance by seam-welding along the flanges 27 in Fig. 2, is a substantially cylindrical conduit 28, which may be formed in two halves seam-welded together at the flanges 29. One end of conduit 28 is closed by a transverse plate 30, which has a portion bent at right angles to form the supporting bracket 31. As may be seen in Fig. 1, the bracket 31 is secured to a Z-shaped bracket 32 by means of suitable threaded fastenings 33, having one or more shims 34 therebetween. Bracket 32 is secured to the nozzle box flange 12 by certain of the threaded fastenings 15. The opposite end of conduit 28 is secured to a similar bracket 32a by means of threaded fastenings 35 and shims 34a, through a U-shaped link 36 secured to conduit 28 by means of pivots 37. This pivoted link construction permits differential thermal expansion between the cooling cap assembly and the nozzle-box structure to which it is secured; and it is more fully described and claimed in U. S. Patent No. 2,362,509 granted November 14, 1944 on an application of Dale D. Streid.

As may be seen in Fig. 3, one end of conduit 28 is arranged to project through a circular opening 38 in the exhaust hood 10. For convenience in assembly and disassembly, some clearance is provided around conduit 28, and this clearance space is sealed by means of a suitable circular packing 39. The packing is tightly compressed into contact with the outer surface of conduit 28 by means of a split clamping band 40 provided with a screw 41 (Fig. 1) arranged to draw together the split ends of the clamping band. Furthermore, packing 39 is held securely against the outer surface of exhaust hood 10 by means of a plate 42 having associated therewith three or more threaded fastenings 43, which may be secured to the exhaust hood 10 and project through tubular spacers 44, in a manner which will be obvious from Figs. 1 and 3.

Secured within conduit 28 is a second smaller conduit 45, which has an open end spaced from the end plate 30 of conduit 28, the other end of conduit 45 projecting through the open end of conduit 28. Conduits 45 and 28 serve as the coolant inlet and outlet respectively, as described below.

It will be understood by those skilled in the art that hot motive fluid is supplied to the flanged nozzle-box inlet 5 and flows through the turbine and exhaust hood as indicated by the arrows 46 in Figs. 1 and 2. The flow of coolant through the cooling cap 11 is as follows. A suitable cooling fluid, such as comparatively cold air from the surrounding atmosphere, is supplied through a suitable conduit (not shown) having an open end which faces into the slip-stream to the projecting open end of conduit 45, whence it flows in the direction of the arrows 47, through the other open end of conduit 45 as indicated by arrows 48, thence through slot 26a in dome member 22 in the manner indicated by arrows 49. Once inside the annular chamber defined by outer dome 22, inner dome 23, and heat transfer rings 25, the cooling fluid flows around as indicated by arrows 50, through the second slot 26b and into the space defined between conduit 45 and conduit 28, as indicated by arrow 51 (Fig. 1). A transverse baffle 28a closes the small openings

defined on either side of inner conduit 45, so that the coolant fluid cannot flow through but is compelled to flow the path 48, 49, 50, 51. The spent coolant fluid may be permitted to discharge into the space surrounding the machine, as indicated by arrows 52, or it may be led away by a suitable duct (not shown), which may have an open end adapted to discharge the fluid in a direction generally opposed to, or aspirated by, the slip stream.

In assembling a turbine embodying my invention, the cooling cap 11 is first secured by means of brackets 32, 32a and threaded fastenings 33 and 35 to the nozzle-box assembly. Any desired clearance between turbine wheel disk 1 and the adjacent edges of cooling cap domes 22, 23 and rings 25 may be secured by selecting shims 34 and 34a of an appropriate thickness and number. It will be apparent that with the exhaust hood removed, the cooling cap 11 is completely exposed for inspection and servicing, while convenient access may be had to the turbine buckets 2 and nozzle diaphragm 7 through the generous opening defined by nozzle-box flange 9. Attention is particularly directed to the fact that the means for supporting the cooling cap is entirely independent of the exhaust hood, so that the cooling cap can be assembled independently of the exhaust hood; and the exhaust hood can be assembled or removed without disturbing the cooling cap. This arrangement greatly facilitates installation and maintenance of the turbine when used in aircraft applications, where space is at a premium and much complex duct-work and other components must be packed into the small space available.

After cooling cap 11 is in place, the exhaust hood 10 is assembled by slipping the opening 38 over the projecting ends of coolant conduits 45, 28, then sliding the exhaust hood axially along the outer surface of conduit 28, meanwhile causing the lower inner portion 53 (Fig. 1) of the exhaust hood flange 16 to follow the dotted path indicated by arrow 54 until flange 16 reaches its final position relative to Z-ring 13. Band clamp 17 may then be assembled around the cooperating flanges and drawn together with bolt 18, thus affixing exhaust hood 10 firmly to nozzle-box flange 9.

The packing for the clearance space at 38 may then be assembled by slipping packing 39 over the projecting end of conduit 28 and assembling the split retainer ring 40 around the packing 39. Plate 42 is then placed on bolts 43 and drawn down onto spacers 44 by tightening the nuts on bolts 43. Packing retainer ring 40 is next drawn tight by means of the screw 41. This causes the packing to be compressed tightly against the outer surface of coolant conduit 28, and against the outer surface of exhaust hood 10.

It will be apparent that the length of spacer tubes 44 may be so selected as to limit the degree to which plate 42 can be drawn down against the retainer ring 40, thus limiting the amount packing 39 can be compressed.

It will be noted that the angular relation between the exterior end of conduit 45 and the exhaust discharge opening 21 may be varied simply by properly locating the opening 38 in the circumference of the exhaust hood.

It will be seen that my invention provides an improved form of radiation type cooling cap, which may be independently supported from the turbine nozzle-box and requires only one opening through the exhaust hood for providing the flow of coolant through the cooling cap. My im-

proved radiation type cooling cap is particularly advantageous when used in connection with an exhaust hood, as shown in the drawings and described above, because of the extreme ease with which the hood may be assembled and removed for servicing, with only one packed joint to be disassembled and only one quick-detachable coupling device for securing the exhaust hood to the nozzle box. In both military and commercial aircraft, an exhaust hood and cooling cap arrangement made in accordance with my invention provides important savings in the time and cost of inspection and maintenance.

While my invention has been particularly described as applied to a gas turbine for driving a supercharger or other device in an aircraft, it will be readily appreciated by those skilled in the art that it is broadly applicable to axial flow high temperature turbines used for other purposes.

What I claim as new and desire to secure by Letters Patent of the United States is:

1. In a high temperature turbine having a bucket-wheel and nozzle means for supplying motive fluid thereto, an exhaust hood detachably secured to the nozzle means around the bucket wheel and having an exhaust gas discharge opening and a single coolant conduit opening and means within the exhaust hood for cooling the exit side of the bucket-wheel disk, said means including a radiation type cooling cap, means securing the cooling cap to the nozzle means at locations surrounded by said hood whereby the exhaust hood may be removed without disturbing the cooling cap, an inlet conduit for supplying a cooling fluid to the cooling cap and a discharge conduit for conducting used coolant from the cooling cap, one of said coolant conduits being contained within the other with said coolant conduits projecting through said coolant conduit opening in the exhaust hood.

2. In a high temperature turbine having a bucket-wheel and a nozzle-box for supplying motive fluid to the bucket-wheel, an exhaust hood detachably secured to the nozzle-box around the bucket-wheel and having a single coolant opening and an exhaust opening, means within the exhaust hood for cooling the exit side of the

bucket-wheel disk, said means including a radiation type cooling cap, means independent of the exhaust hood securing means securing the cooling cap to the nozzle-box at locations enclosed by said hood, an inlet conduit for supplying a cooling fluid to the cooling cap and a discharge conduit for conducting used coolant from the cooling cap, said inlet conduit being contained within the coolant discharge conduit and the end of said coolant conduits projecting through said coolant opening in the exhaust hood.

3. In a high temperature turbine having a bucket-wheel and a nozzle-box for supplying motive fluid thereto, an exhaust hood detachably secured to the nozzle-box around the bucket wheel and having a single coolant opening and an exhaust opening, means within the exhaust hood for cooling the exit side of the bucket wheel disk, said means including a radiation type cooling cap, means supporting the cooling cap from the nozzle-box, said supporting means being enclosed by said exhaust hood, an inlet conduit for supplying a cooling fluid to the cooling cap, a discharge conduit for conducting used coolant from the cooling cap, the coolant inlet conduit being contained within the discharge conduit and the ends of said coolant conduits projecting through said single coolant opening in the exhaust hood, and packing means for sealing the clearance space between said coolant conduits and the exhaust hood.

JOSEPH S. ALFORD.
